UNITED STATES PATENT OFFICE

EVENCE COPPEE, OF BRUSSELS, BELGIUM

COKE OVEN

Application filed May 26, 1927, Serial No. 194,303, and in Belgium September 4, 1928.

The present invention relates to improvements in or modification of the oven described in my copending patent application filed the 15th June 1926 Serial No. 116,085.

5 According to this copending application, the wall of the coke oven comprises an even number of groups of vertical flues each of which is connected to the one adjacent to it by a communication chamber, these chambers 10 being disposed alternately near the top and near the bottom along the length of the wall. Further, the whole of the fluid burning agent is admitted at the base of the first group with a fraction only of the total amount of gas 15 serving for the combustion, called primary gases, while the balance of the gas i. e., the secondary gas is admitted along the path of the burning current.

In the oven described, in my copending 20 application Serial No. 116,085 the admission of secondary gas takes place only in the upper communication chambers between one group to the next near the partitions separating these groups.

25 Now, the groups of descending flues which are located beyond the points at which these admissions of secondary gas are made absorb approximately 90 to 95% of the heat of the flame absorbed by a descending group and 30 the ascending group which follows it. As a consequence the efficiency of these last groups is practically zero.

In order to remove these disadvantages, the present invention provides, in addition 35 to the admissions of secondary gas into the upper communication chambers of the walls, for admissions of secondary gas into the lower communication chambers.

In the accompanying drawing, the figure 40 is a longitudinal section through a part of a coke oven wall according to the invention.

It shows, that the wall is formed by a series 45 of an even number of groups of vertical combustion flues 3. These groups, which are separated from each other by partition walls 1, are connected together by communication chambers 2 placed alternatively at their upper and lower ends over the whole length of the wall.

50 By adopting the stage of regeneration for

which the current circulates from left to right, in the wall considered, it is seen that the hot air coming from a regenerator 4 is distributed by ducts 5 arranged at the base of the uptake flues of the left end group according to the 55 draught which is regulated by means of dampers 14 located at the upper part of the flues. A part of the gases serving for the combustion, called primary gas, is drawn through a pipe 6 into a distributing duct 7 and is distributed in the same flues 3 by means of calibrated and removable pipes 9 to which access may be had through inspection holes 10 formed in the roof of the wall.

60 The mixture of burning air and gas thus formed rises in the first group of flues 3 and changes direction as it passes from each subsequent group so that a flow as through baffles is obtained.

65 Admission ports 11, 12, 13, 16 and 17 for secondary gas are provided in all the communicating chambers so that all the consecutive groups of flues will have the same efficiency.

70 Dampers 15 similar to the dampers 14 enable the equal distribution of the gaseous current in the vertical flues forming the consecutive groups to be obtained.

What I claim is:

75 In a coke oven, a coking chamber, a heating 80 wall for said chamber, comprising a series of an even number of at least four groups of vertical combustion flues, said groups being communicatively connected together in series by horizontal bus flues above, and at least 85 one horizontal bus flue below, said vertical combustion flues, means for admitting air into and discharging burnt gas alternately from each of the outer groups, means for admitting fuel gas into each of the outer groups, 90 and means for admitting fuel gas directly into each of the horizontal bus flues.

95 In testimony whereof I affix my signature.

EVENCE COPPEE.
